(57) **CLAIM**

The ornamental design for a door operator unit, as shown and described.

DESCRIPTION

FIG. 1 is a rear view of a door operator unit;

FIG. 2 is a right side view of a door operator unit;

FIG. 3 is a bottom view of a door operator unit;

FIG. 4 is top view of a door operator unit;

FIG. 5 is a front view of a door operator unit;

FIG. 6 is a rear isometric view of a door operator unit; and,

FIG. 7 is a front isometric view of a door operator unit.

The broken lines shown are included for the purpose of illustrating portions of the door operator unit that form no part of the claim.

1 Claim, 7 Drawing Sheets
